UNITED STATES PATENT OFFICE.

WILLIAM HENRY HARRISON, OF PHILADELPHIA, PENNSYLVANIA.

GARMENT HANGER.

Application filed February 9, 1924. Serial No. 691,801.

To all whom it may concern:

Be it known that I, WILLIAM HENRY HARRISON, a citizen of the United States, residing in Philadelphia, in the county of Philadelphia and State of Pennsylvania, have invented certain new and useful Improvements in Garment Hangers, of which the following is a specification.

This invention relates to garment hangers of the kind adapted to support men's clothing. Ordinarily garment hangers of this class are constructed to support a suit of clothes, viz, coat, trousers and waist-coat, but inasmuch as special kinds of socks, ties, shirts, etc., are often worn with each suit, it is desirable to associate these articles with each other when not being worn and while hung, closeted or packed for future use. One object of my invention is to provide a hanger which is adapted to support these various articles in a secure and convenient manner, and another object of the invention is to provide a hanger which will so hold the associated articles that they may be properly packed in a traveling trunk or other such receptacle.

According to my invention, I provide a main cross-piece so shaped as to support the waist-coat and coat of the suit in such manner as to retain the natural creases in these articles, and another cross-piece adapted to support one or more pairs of trousers and which is so connected to the main cross-piece that undue strain on either member of the hanger is avoided, and means is provided for holding socks, ties and other parts of the clothing. The hanger is also so constructed that with the clothes thereon it may conveniently be placed in a trunk or other suitable receptacle and so supports the clothes as to hold them in such manner as to prevent "mussing" or the formation of creases or wrinkles in undesirable places.

My improvements are illustrated in the accompanying drawings, in which:—

Figure 1 is a perspective view of a garment hanger constructed in accordance with my invention.

Figure 2 is a front elevation of the hanger and illustrates how a suit of clothes and other articles may be supported thereon.

The lower or main cross-piece A is preferably made of wood or other anti-rust material. It is, for the most part, straight or slightly curved, and it is provided on its opposite ends with enlarged, rounded termina-

nals A'. The upper cross-piece B is also preferably made of wood and it is provided at its opposite ends with knobs B' which are preferably of metal. As shown, each knob B' is formed on a tubular member b which fits an end of the member B. These knobs are for the purpose of connecting the hanger with certain guides or sockets provided in a traveling trunk of the kind shown in my application for patent filed February 9, 1924, Serial No. 691,800.

In order to connect the upper and lower cross-pieces I employ strong lengths of cord C and D which are preferably disposed in the manner shown. One length of cord C is looped in its central portion at c centrally above the upper cross-piece and carries a hook E which may be detachably connected with the loop c. The cord C extends in opposite directions from the loop c to the end portions of the upper cross-piece through which it extends, as shown, and each branch of the cord is knotted at c' below the cross-piece. From the end portions of the upper member B the two branches of the cord extend in opposite directions along the underside of said member and then extend through eyes or loops f in a strengthening member F preferably made of piano wire. This member F is attached to the end portions of the member B, in the manner indicated at f'. From the eyes f the cord C extends to the opposite end portions of the lower cross-piece A and are then passed through the end portions of the lower cross-piece and are knotted at a in such manner as to hold the lower cross-piece in a horizontal position. From the undersides of the member A the two ends of the cord pass downwardly, the free end portions being employed for a purpose presently described. The other length of cord D has its central portion arranged between the eyes f of the wire F from which the cord extends downwardly, being tied at x to the branches of the cord C. From these knots x the cord D extends downwardly and outwardly through the lower cross-piece A and each branch of the cord, after extending through the member A, is carried across the middle portion thereof and then through the member A, being knotted at y above the member A. The free ends of the cord D are loose, as shown, there being extra portions of the cord so that the knots y may be tied in different places to either increase or decrease

the distance between the upper and lower cross-pieces. While this way of arranging the cords is preferred, the invention is not limited to this precise arrangement, but it will be seen that the strain on the hanger members is distributed in such manner as to distribute the weight of the clothing and prevent breakage of any of the members composing the hanger.

Figure 2 illustrates the hanger shown in Figure 1 and indicates how different articles of clothing may be supported thereon. The drawings indicate how a coat and trousers are supported on the hanger. It will be understood that the waist-coat is beneath the coat, and I have also indicated how a pair of socks may be supported. Experience has demonstrated that ties, shirts and other articles may be supported on a hanger of the construction shown so as to support and associate a complete change of clothing. Clothing supported in the manner shown in Figure 2 may be suspended from a horizontal rod, from hooks or other permanent fixtures and when needed can be easily withdrawn from a place of storage and removed from the hanger. The hanger is especially designed to support articles of clothing assembled in the manner described and in convenient condition for transfer to a traveling trunk especially designed to contain a plurality of suits. Such a trunk is shown in my application for patent filed February 9, 1924, and reference is made to that application for further particulars. It will be observed, by reference to Figure 2, that the lengths of cord depending from a hanger are passed through the sleeves of the coat, brought together and tied at C'. It will also be observed that the rounded ends A' of the lower cross-piece extend well into the shoulder portions of the sleeves so as to hold the coat as to retain the natural creases and prevent the formation of creases in undesirable places. The upper and lower cross-pieces being flexibly connected may, when not used to support clothing, be brought together and tied by the cord so as to occupy a very small space. As before stated, the distance between the upper and lower cross-pieces A and B may be adjusted by properly locating the knots α and γ .

When in use the weight of the clothes

exerts a strain on the cordage and thereby the articles of clothing which are held by the cordage on the cross-piece are securely fastened.

I claim as my invention:

1. A garment hanger comprising upper and lower cross pieces, flexible connections joining the two cross pieces and cords extending downwardly below the lower cross piece to a greater extent than the sleeve length of a coat and providing means for holding the sleeve of a coat in proper position for hanging or packing. 55

2. A garment hanger comprising upper and lower cross-pieces, cords connecting the two cross-pieces and holding them a suitable distance apart and which extend downwardly below the lower cross-piece to a greater extent than the sleeve length of a coat and provide means for holding the sleeves of a coat in proper position for hanging or packing. 60

3. A garment hanger comprising upper and lower cross-pieces, a wire secured to the ends of the upper cross-piece and provided with loops in its middle portion, and cords connected with the upper cross-piece extending through the loops of the wire and connected with the end portions of the lower cross-piece. 65

4. A garment hanger comprising upper and lower cross-pieces, a wire secured to the ends of the upper cross-piece and provided with loops in its middle portion, a cord extending through the end portions of the upper cross-piece and through the loops of the wire and then through the end portions of the lower cross-piece, and another length of cord extending through the loops of the wire and through the middle portion of the lower cross-piece. 70

5. A garment hanger comprising an upper cross-piece, a lower cross-piece, a wire attached to the ends of the upper cross-piece and having loops near the middle portion of said upper cross-piece, and lengths of cord attached to the upper cross-piece which extend through said loops and have diagonal portions which extend to the ends of the lower cross-piece. 75

In testimony whereof, I have hereunto subscribed my name.

WILLIAM HENRY HARRISON.
